UNITED STATES PATENT OFFICE.

WILLIAM H. HARRIS AND JOHN C. KAFER, OF WASHINGTON, DISTRICT OF COLUMBIA.

ATTACHMENT FOR BOILER-FURNACES.

SPECIFICATION forming part of Letters Patent No. 373,557, dated November 22, 1887.

Application filed May 20, 1887. Serial No. 238,850. (No model.)

To all whom it may concern:

Be it known that we, WILLIAM H. HARRIS and JOHN C. KAFER, citizens of the United States, residing at Washington, in the District 5 of Columbia, have invented a new and useful Improvement in Attachments to Boiler-Furnaces, of which the following is a full, clear, and exact description.

This invention relates to improvements in 10 devices to prevent the leakage of gases from the furnace and feeding air to furnaces when operated under forced draft, or where the pressure of air under the grate is greater than the atmospheric pressure.

15 The object is to prevent the gases from a furnace having a closed ash pit and forced draft being forced through the openings around the furnace-door into the fire-room. The air entering the ash-pit is freely admitted to the 20 space between the inner and outer plates of the furnace door, and as this air is under a higher pressure than the air or gases in the furnace the air between the inner and outer plates of the furnace-door will be forced into 25 the furnace on one side and into the fire-room on the other, preventing the escape of gases from the furnace and keeping the furnace-door cool.

It will be understood that this is not intended as an air-feeding device for supplying 30 air to the furnace through the furnace-door, but that the special object is to keep a sufficient pressure of air inside of the door and between its walls to prevent the passage of 35 furnace-gases from the furnace into the fire-room. The leakage of air from within the door into the furnace and fire-room will be only what is due to the fact that the door will ordinarily fit loosely in its frame, unless more 40 air is required over the fuel, when air can be supplied through holes in the inner plate of the furnace-door or furnace-front, as is now done in furnace-doors and furnace-fronts using a natural draft.

45 When it is necessary to open the furnace-door for any purpose while using forced draft, the damper in the air-pipe leading to the ash-pit is first closed, reducing the pressure in the furnace. Then the furnace door can be opened

and the furnace operated as when using natural draft. 50

The ash-pit is closed by a door made tight by a gasket or other means, and provided with suitable means for securing the door.

The damper is operated from the outside of 55 the air pipe or box, there being a damper to each ash-pit or furnace. By closing the damper the air-pressure in the furnace to which it is connected is reduced, the furnace-door may be opened, and the fire cleaned or coaled, while 60 the pressure in the ash-pits of other furnaces is not reduced, but maintained to the maximum of air-pressure supplied by the blowers.

The method of increasing the combustion by 65 forcing air into an air-tight fire-room, or properly a closed fire-room, has the objections that it is difficult to make the bulk-heads perfectly air-tight; that air-locks are required for the ingress and egress of firemen; that the air-pressure is rapidly reduced when a furnace-door is opened, and that the cold air rushing in the furnace when the furnace-door is open impinges on the tube-sheets and tubes, causing contraction of the metal and the seams and tubes to leak, while the air-pressure in the fire-room is reduced, lessening the rate of combustion in the other furnaces. Blowing the air 70 under the grate obviates these difficulties; but when the air-pressure is increased to such an extent as to make the pressure in the furnace 75 greater than the normal pressure of the atmosphere the gases are forced into the fire-room through the cracks and openings around the furnace-door and frame, making the door red-hot and the atmosphere of the fire-room un- 80 bearable.

To prevent the escape of the furnace gases when using a closed ash-pit, a combination of 85 the two systems has been used, having a closed ash-pit with air-pressure under the grates and a closed fire-room with an air-pressure in the fire-room greater than the pressure of the gases in the furnace, but less than the pressure under the grates in the closed ash-pit. The pressure in the furnace is less than the pressure 90 under the grates on account of the resistance of the fuel to the passage of the air. When the furnace-door is opened, the pressure of air 95

in the fire-room being about the same as the furnace gases, there is no great inflow of cold air or outflow of gases; but with this combination the fire-room is not properly ventilated 5 and the heat becomes unbearable.

By our invention the difficulties of the closed fire-room, the closed ash-pit, and the combination of the two systems are avoided, thus permitting an open fire-room for the ingress and 10 egress of the firemen, free ventilation of the fire-room, while a high air-pressure can be maintained under the grates and in the furnaces without forcing the furnace gases into the fire-room.

15 Reference is made to the accompanying drawings, forming part of this specification, in which similar letters refer to similar parts throughout the several views.

Figure 1 is a section through the furnace, 20 ash-pit, furnace-front, furnace-door, air pipe or box, damper, and ash-pit door. Fig. 2 is a partial front elevation and a partial section through the furnace-front and air pipe or box.

A represents the furnace; B, the ash-pit; C, 25 the air pipe or box; D, the furnace-door, with double plates J and K; E, the furnace-front and door-frame, with the passage F and openings H to admit air under pressure from the ash-pit B or air-box C, through the passage 30 F and H, to the space between the front and back plates forming the furnace-front and to the space between the two plates J K of the furnace-door, thereby air-packing the furnace-door and preventing any leakage of gases from 35 the furnace to the fire-room, also providing for a leakage of air from the spaces between the two plates forming the furnace-door to the furnace and to the fire-room, if there is any opening in the furnace-door, thereby keeping 40 the furnace-door cool. The openings H may be of any convenient form or size and as near to each other or as far apart as may be desired.

P is the dead-plate.

45 L is the damper in the air-box C, to be operated by the lever N, or other suitable means.

M is the ash-pit door, secured to the front of the ash-pit or projection of the furnace by the movable clamps O, or other suitable 50 means.

R is a deflecting-plate to deflect the air to the openings in the dead-plate and furnace-front.

When the forced draft is not used, this ash-pit door can be removed from the front of each ash-pit and the furnaces operated under natural draft.

55 The ash-pit door is to be made air-tight, or sufficiently so to prevent any great leakage of

air from the ash-pit to the fire-room, by a gas- 60 ket or other suitable means.

Having thus described our invention, what we claim as new, and desire to secure by Letters Patent, is—

1. The method of preventing the escape of 65 furnace-gases from the furnace of a steam-boiler into the fire-room around the furnace-door by air-packing the door, consisting in supplying air under pressure from the ash-pit through openings in the door-frame or furnace-front and dead-plate, wholly or partly inside the furnace, to the space between inner and outer plates of the furnace-door and door-frame or furnace-front, substantially as shown and described. 75

2. The combination of the furnace-door D, formed of plates separated to form an air-chamber for air under pressure from the ash-pit, with the hollow door-frame or furnace-front E, wholly or partly inside the furnace, 80 perforated in the arch with openings H, to supply air to said chamber from the ash-pit, and the perforated dead-plate P, with openings from the ash-pit to supply air from it to the space between the plates of door and to the 85 hollow door-frame or furnace-front, substantially as shown and set forth.

3. The combination of the hollow perforated door-frame E with the passages F, the hollow furnace door D, the perforated dead-plate P, 90 the openings in the dead-plate between the ash-pit and the air-chamber formed by the door, the air-duct C, leading to the ash-pit, and the damper L, for closing the duct C, substantially as shown and set forth. 95

4. The combination of the hollow furnace-door D, having, when closed, its interior in communication with the closed ash-pit B through openings in the door-frame or furnace-front and dead-plate, by which air under 100 pressure may be supplied from the closed ash-pit for the purpose of air-packing the furnace-door and preventing the escape of furnace-gases through or around the furnace-door into the fire-room, substantially as shown and set 105 forth.

5. The combination of the furnace-front E, with passage F and openings H, the furnace-door D, the closed ash-pit B, the deflecting-plate R, the air pipe or duct C, the damper L, 110 the lever N, and the ash-pit door M, in connection with a boiler operated under forced draft, for the purpose specified.
